COMBINATION INSTANTANEOUS AND DELAY FUSE

Harold M. Brayton, Dover, N. J., assignor to
American Armament Corporation, New York,
N. Y., a corporation of Delaware

Application November 12, 1940, Serial No. 365,355

4 Claims. (Cl. 102—74)

The invention relates to a combination instantaneous and delay fuse of the general type disclosed in my U. S. Patent No. 1,672,150 of June 5, 1928, and it aims to so improve upon the prior construction as to provide for greater safety and for greater efficiency.

With the foregoing in view, the invention resides in the novel subject matter hereinafter described and claimed, description being accomplished by reference to the accompanying drawings.

Figure 1 is a central longitudinal section through one form of the fuse.

Figures 2, 3, 4 and 5 are transverse sectional views on the correspondingly numbered line of Fig. 1.

Figure 6 is a view similar to Fig. 1, but showing a more slender fuse for use with projectiles having longer ogives.

Figures 7 and 8 are transverse sectional views on the correspondingly numbered lines of Fig. 6.

The form of construction shown in Figs. 1 to 5 will first be described.

The fuse body comprises a main one-piece front section 10 having a tapered nose 11, and a cup-like rear section 12 threaded upon the rear end of said section 10, a slight space 13 being preferably left between the front extremity of said section 12 and the adjacent portion of said section 10. The rear section 12 is to be threaded into the front end of a conventional projectile 14, and the front section 10 is provided with an appropriate flange 15 to abut said projectile. A suitable container 16 is threaded upon the rear end of the section 12 or otherwise connected therewith to contain a booster charge 17, and a rotor 18 is pivotally mounted in the body section 12 to contain a conventional detonator 19, said rotor being normally held in unarmed position by centrifugally released pins 20. At 21, I have shown a socket in the front side of the rotor 18, said socket being disposed axially of the fuse when the rotor is in unarmed position (Fig. 2). While a corresponding socket was essential in the old patent above mentioned, to permit set-back of the firing pin when firing the projectile, the rotor 18 of the improved construction may well be devoid of such a recess if desired, as positive provision is made for holding both the instantaneous-action firing pin and the delayed-action firing pin which are now used, against set-back.

The rear end of the body section 10 is formed with a centrally disposed cylindrical socket 22 which opens through the rear extremity of said section 10, the rear end of said socket, however,

being provided with a suitably secured closure plate or ring 23 which abuts a plate 24 within the body section 12, said plate 24 serving to retain the rotor 18 in its receiving recess 25. The front 5 end of the socket 22 is provided with an integral rearwardly projecting boss 26 which is centrally disposed. This boss is snugly received in the front portion of a fixed sleeve 27 which is disposed within and spaced from the side wall of 10 the socket 22, the rear end of said fixed sleeve 27 being in solid contact with the plate or ring 23. The boss 26, no equivalent of which was present in the old patent above mentioned, positively holds the front end of the fixed sleeve 27 15 centered and thus overcomes any liability of parts hereinafter described binding instead of freely sliding.

A piston-like delayed-action firing pin 28 is 20 slidably mounted in the fixed sleeve 27 and is provided at its rear end with rearwardly projecting firing prongs 29. A suitable spring 30 acts rearwardly upon the firing pin 28 but is normally held against action by impact released means now to be described.

25 The periphery of the firing pin 28 is formed with a groove 31 which normally registers with openings 32 extending from the inner to the outer side of the fixed sleeve 27, said groove and openings normally receiving a plurality of balls 33.

30 These balls are held normally in place by an outer slidable sleeve 34 which surrounds the fixed sleeve 27 and slidably contacts with the side wall of the socket 22 and with said fixed sleeve, said slidable sleeve 34 being normally held in a 35 rearward position by a suitable spring 35. Forward movement of this sleeve 34 is normally prevented by centrifugally released pins 36. After these pins have been released by rotation of the projectile during flight, the sleeve 34 is free to slide forwardly by momentum when the projectile is suddenly decelerated, for example, when the impact of striking a target occurs. This forward sliding of the sleeve 34 releases the balls 33 and they may fly outwardly by centrifugal force into

40 an internal channel 37 in said sleeve, thus releasing the firing pin 28 in readiness for rearward movement to cause the prongs 29 to fire the detonator 19, this detonator having been previously set at armed position by means of the centrifugally moved rotor 18, upon release of the pins 20. The rearward movement of the firing pin 28 will not occur immediately when the projectile strikes the target, but on the contrary said pin 28 will remain forward, holding the spring 30 compressed as long as the forward inertia force

due to retardation of the projectile equals the strength of the spring 30. Whenever this resistance has decreased sufficiently, however, the spring 30 operates the firing pin 28 to fire the detonator. Thus, the fuse will not explode when set for delay action until the projectile has passed through the target or come to rest in it, i. e., until practically all resistance to penetration has ceased.

The balls 33 and associated parts prevent set-back of the delay-action firing pin 28 when the projectile is fired and, therefore, even if the rotor 18 should have been assembled in armed position, the detonator 19 cannot be accidentally fired which was not true of the old patented construction.

An instantaneous-action firing pin 33 is provided at its front end with a striker 39 suitably secured at 40 to said firing pin, said striker being mounted directly in a longitudinal bore 41 in the nose portion 11 of the fuse body, instead of in a separate tube as in the old structure. The front portion 42 of the firing pin 33 is of greater diameter than the remainder of said firing pin, and it will be seen from Fig. 1 that the rear portion of said firing pin extends slidably through a central bore 43 in the delay-action firing pin 28. At the juncture of the two diameters of the firing pin 33, there is a rearwardly facing shoulder 44. Normally this shoulder nearly abuts a centrifugally released pin 45 slidable in the body section 10 and thus the entire firing pin is held against set-back when firing the projectile from the gun, again insuring that the detonator shall not be fired even though the rotor 18 may have been assembled accidentally in armed position. No equivalent of the separate instantaneous-action firing pin 33 and the associated centrifugally released pin 45 were present in the patented structure above mentioned.

A suitable portion of the firing pin 33 and an adjacent portion of the body section 10 are formed with screw threads or the like 46 and 47 which may be engaged by rotation of the striker 39 and said firing pin, when the fuse is to be set for delayed action, preventing the firing pin 33 from operating upon impact of the projectile with the target and leaving the firing under control of the delayed-action firing pin 28. When the threads or the like 46 and 47 are disengaged, however, the instantaneous-action firing pin 33 will operate as soon as the striker 39 contacts with the target, the pin 45 having been previously released by centrifugal force.

In the more slender construction shown in Figs. 6 to 8, the rear section 12^a of the fuse body is threaded into instead of onto the rear end of the front section 10^a, and it is this front section which is to be threaded into the projectile 14^a. The majority of the parts shown in these views are practically the same as corresponding parts above described, except with regard to size and proportion. There are certain changes, however, to which attention will be invited. The front end of the fixed sleeve 27^a is centered by a boss 26^a on a plate 26^b, which plate is snugly fitted into the front end of the socket 22^a, instead of having a boss integral with the front wall of the socket as above described. The spring 35^a for the slideable sleeve 34^a is also disposed externally of said sleeve instead of internally thereof. The two firing pins 28^a and 33^a are associated in the same manner as the corresponding pins above described, the balls 33^a hold 28^a against rearward movement until released, and pin 45^a holds 33^a

against rearward movement until released. Sleeve 34^a is, of course, normally held against forward movement by centrifugally released pins 36^a.

The rotor 18^a is pivotally mounted in a recess 25^a on a pivot pin 50 which is at right angles to the axis of the fuse, said rotor being normally held in unarmed position by centrifugally released lock pins 20^a. The rotor is suitably overbalanced to cause it to move to armed position under the action of centrifugal force when the pins 20^a are released, a stop pin 51 extends across the recess 25^a to limit the movement of the rotor to armed position, and a centrifugal lock pin 52 carried by said rotor, is employed to engage a socket 53 in a wall of the recess 25^a (Fig. 8) to lock said rotor in armed position. The rotor carries a stab-type primer 54 and a detonator 55 to be fired by said primer, both primer and detonator being loaded with highly compressed sensitive explosive. Even should the sensitive elements explode with the rotor 18^a in unarmed position, no disaster would occur, as the explosive elements 56 and 57 in rear of said rotor would not be disturbed in any way. These elements 56 and 57 are preferably of tetryl.

In both forms of the invention, it will be observed that no set-back of one firing pin or the other occurs when firing the projectile from a gun. Thus, neither firing pin can move into the socket 21 or into other engagement with the rotor to interfere with movement of the latter to armed position. The new association of slidably engaged firing pins operates better than the arrangement shown in the patented structure and there are only two springs required, there being no spring in the rear end of the sleeve 27, whereas a spring at this location in the patented mechanism was not only difficult to construct of proper tension but often caused trouble. The spring 58 now employed for sliding the instantaneous-action firing pin forward, need only be of sufficient strength to prevent the action of air pressure against the striker 39 from sliding said striker and pin rearwardly, which was not true of the patented structure. To prevent the spring 58 from catching in the inner end of the socket 59 in which it is located, when turning the striker 39 to set the fuse for either delayed or instantaneous action, it is preferable to interpose a washer 60 between said spring and said inner end of socket 59.

In addition to advantages previously briefed for the improved structure, it is highly important to observe that as both firing pins are held against set-back when the projectile is being fired from a gun, there is no possibility whatever of either of said pins exploding said projectile in the gun barrel, even if it should have been possible to assemble the rotor 18 or 18^a in armed position. The improved structure thus possesses a much greater element of safety than the patented construction above mentioned. Moreover, the new structure has been found to possess greater strength with no danger of the fuse shearing off flush with the front end of the projectile when striking at low angles. Also the striker 39 is much more stably mounted and its mounting means will not be injured and rendered ineffective when striking at low angles, as was the case with the patented construction. Moreover, the new construction associated with the striker is much easier to manufacture and less expensive.

Excellent results have been obtained from the construction shown and described and it is, there-

fore, preferably followed. However, within the scope of the invention as claimed, minor variations may of course be made.

What is claimed is:

1. In a combination instantaneous and delayed-action fuse, a body having a central socket which opens through its rear end, a fixed sleeve in said socket and spaced from the side wall thereof, a transverse plate secured to the rear end of said body and abutting the rear end of said sleeve, said plate having a central opening and said sleeve being provided with openings from its inner to its outer side, a piston-like delayed-action firing pin slidable in said sleeve and having an axial bore, an instantaneous firing pin slidable in said bore and projecting rearwardly from said piston-like firing pin, the rear end of the latter having rearwardly projecting firing prongs spaced around said instantaneous-action firing pin, the periphery of said piston-like firing pin being provided with a groove registering with said openings of said sleeve, a spring in said socket for forcing said piston-like firing pin rearwardly, balls seated in said registering groove and openings and normally preventing rearward movement of said piston-like firing pin, an outer sleeve slidably surrounding said fixed sleeve and normally holding said balls in said openings thereof, said outer sleeve contacting slidably with the wall of said socket and being forwardly slid- able to release said balls when the projectile is suddenly decelerated, and centrifugally released means for normally holding said outer sleeve against forward movement.

2. In a combined instantaneous and delayed-action fuse, a body, an instantaneous-action firing pin slidably mounted longitudinally in said body and having a striker at its front end and a detonator-firing portion at its rear end, cooperable manually engageable pin-holding means on said body and firing pin for holding the latter against operation when desired, a separate delayed-action firing pin slidably mounted longitudinally in said body and having a detonator-firing portion at its rear end, an operating spring in said body urging said delayed-action firing pin rearwardly, a centrifugally released member movably mounted in said body and normally engaging said instantaneous-action firing pin to hold it against rearward movement, additional pin-holding means movably mounted in said body and engaging said separate delayed-action firing pin to normally hold it against rearward movement, said additional pin-holding means including a momental member mounted in said body for movement to a forward position in which it effects release of said delayed-action firing pin, a second centrifugally-released member mounted in said body and normally abutting said momental member to hold it against forward movement, and yieldable means in said body exerting a rearward force on said momental member to prevent forward movement of the latter until said body is suddenly decelerated.

3. In a combined instantaneous and delayed-action fuse, a body, an instantaneous-action firing pin slidably mounted longitudinally in said

body and having a striker at its front end and a detonator-firing portion at its rear end, cooperable manually engageable pin-holding means on said body and firing pin for holding the latter against operation when desired, a separate delayed-action firing pin mounted slidably in said body and slidably surrounding said instantaneous-action firing pin, said separate delayed-action firing pin having a detonator-firing portion at its rear end, an operating spring in said body urging said delayed-action firing pin rearwardly, a centrifugally released member movably mounted in said body and normally engaging said instantaneous-action firing pin to hold it against rearward movement, additional pin-holding means movably mounted in said body and engaging said separate delayed-action firing pin to normally hold it against rearward movement, said additional pin-holding means including a momental member mounted in said body for movement to a forward position in which it effects release of said delayed-action firing pin, a second centrifugally released member mounted in said body and normally abutting said momental member to hold it against forward movement, and yieldable means in said body exerting a rearward force on said momental member to prevent forward movement of the latter until said body is suddenly decelerated.

4. In a combined instantaneous and delayed-action fuse, a body, an instantaneous-action firing pin slidably mounted longitudinally in said body and having a striker at its front end and a detonator-firing portion at its rear end, cooperable manually engageable pin-holding means on said body and firing pin for holding the latter against operation when desired, a separate delayed-action firing pin slidably surrounding said instantaneous-action firing pin, said separate delayed-action firing pin having a detonator-firing portion at its rear end, an operating spring in said body urging said delayed-action firing pin rearwardly, a centrifugally released member movably mounted in said body and normally engaging said instantaneous-action firing pin to hold it against rearward movement, a fixed sleeve extending longitudinally within said body and slidably receiving said delayed-action firing pin, said fixed sleeve having an opening from its inner to its outer side, a ball in said opening engaged with said delayed-action firing pin to normally hold the latter against rearward movement, a momental sleeve slidably surrounding said fixed sleeve and normally occupying a rearward position in which it holds said ball engaged with said delayed-action firing pin, said momental sleeve being forwardly slidable to release said ball and thereby release said delayed-action firing pin, a second centrifugally released member movably mounted in said body and normally abutting said momental sleeve to prevent forward movement thereof, and yieldable means in said body exerting a rearward force on said momental sleeve to prevent forward movement of the latter until said body is suddenly decelerated.

HAROLD M. BRAYTON.
